United States Patent Office.

A. P. CINDEL AND MARTIN VOGEL, OF JACKSONVILLE, ILLINOIS.

Letters Patent No. 98,148, dated December 21, 1869.

IMPROVED WASHING-MACHINE.

The Schedule referred to in these Letters Patent and making part of the same.

To all whom it may concern:

Be it known that we, A. P. CINDEL and MARTIN VOGEL, of Jacksonville, in the county of Morgan, and State of Illinois, have invented a new and valuable Improvement in Washing-Machines; and we do hereby declare that the following is full, clear, and exact description of the construction and operation of the same, reference being had to the annexed drawings, making a part of this specification, and to the letters and figures of reference marked thereon.

Figure 1, of the drawings, is a central vertical section of our invention, taken through the line *xx*.

Figure 2 is a horizontal section of the same, taken through the line *yy*.

Our invention relates to washing-machines, and consists, mainly, in the construction and novel arrangement of devices, whereby certain currents are imparted to the water, in such directions that they will serve an efficient purpose in cleansing the goods.

The goods to be cleansed are placed in the wooden receptacle or tub *A*, whose general shape is that of a frustum of a cone.

For the purpose of partially confining the goods to the space between the revolving dasher and the fixed wash-boards, hereinafter described, a circular ledge, *B*, is attached to the tub, being secured to its inner surface some inches below the top.

There are also attached, to the inner surface of the tub, six or more wash-boards, usually formed of corrugated zinc, which extend from the bottom of the tub to the ledge *B*.

These wash-boards are lettered *C*.

D is a rod whose lower end is fitted as a stopper to the waste-aperture. This rod passes up through the circular ledge *B*, and is, therefore, easily reached, when necessary.

E is a zinc plate, lining the central portion of the bottom of the tub, the centre of which is reamed out, to form a socket or bearing for the pin *a*, fixed in the centre of the bottom of the dasher *F*.

The dasher *F* consists of a horizontal disk of wood, *f*, to which is secured a perpendicular shaft, *f'*, terminating in a bevel-pinion, *g*, and bearing-pin *h*.

Secured, tangentially, to the shaft *f'* are the dash-boards *G*, each of which has a vertical arm extending up along the shaft *f'*, and a horizontal arm, extending out over the disk *f*.

H is a cross-bar, of wood, whose ends are fitted in seats, formed in the inner edge of the top of the tub, in such a manner as to be easily removed therefrom, when necessary, for cleansing or other purposes.

Power is communicated by means of the crank *K*, the shaft of which is supported in iron bearings, screwed to the cross-bar *H*.

This shaft terminates in a bevel-wheel, *k*, which engages with the bevel-pinion *g* of the dasher.

m designates a plate, secured to the cross-piece *H*, and pierced, to form a bearing for the pin *h*, of the dasher.

L is a cover, usually placed over the cross-bar *H*, in such a manner as to protect the shaft and pinions from moisture, as far as possible; as well as to protect the goods from the iron, as they are placed in or removed from the tub.

This cover *L* is secured by bolts and thumb-nuts, each bolt being formed with a cross-piece at the end, which is secured under the lugs of the ear *n*, screwed to the side of the tub.

The central portion of the bottom of the dasher is fitted with a piece of zinc, similar to that on the bottom of the tub.

A small leather washer is sometimes employed between these two zinc plates to prevent undue wearing thereof.

The open spaces on each side of the cross-bar *H*, in the top of the tub, are closed, when so desired, by covers, in the form of wooden segments, fitted to the spaces spoken of.

The whole is usually mounted upon a three-legged frame, *Z*, in order that it may be more easily operated.

Attention is particularly directed to the simplicity of this machine, as well as its completeness. Also to the fact that the covers, bolts, gearing, cross-bar, and dasher, can all be removed from the tub in a few seconds, if necessary, and as easily replaced.

By the tangential position of the dash-boards, a longer sweep is secured than would be the case if they were attached radially.

The vertical arm of the dash-board, it will be perceived is designed to give an outward or centrifugal current to the water in the tub, while the horizontal arm is arranged to create an upward current, and the formation of the wash-boards, fixed to the side of the tub, is such that they directly meet the first or centrifugal current, thus causing a reverse or back flow.

What we claim as our invention, and desire to secure by Letters Patent, is—

The washing-machine, herein described, having fixed wash-boards *C* *C*, separate from each other, the dasher *F*, ledge *B*, bevel-wheels *g* and *k*, cross-bar *H*, and cover *L*, constructed and arranged to operate substantially as specified.

In testimony that we claim the above, we have hereunto subscribed our names, in the presence of two witnesses.

A. P. CINDEL.
MARTIN VOGEL.

Witnesses:

JACOB R. DAVIDSON,
JEREMIAH PIERSON.
